UNITED STATES PATENT OFFICE.

FRANK WILLIAM MILES, OF ST. LOUIS, MISSOURI, ASSIGNOR TO HYDRAULIC PRESS
BRICK COMPANY, OF ST. LOUIS, MISSOURI, A CORPORATION OF MISSOURI.

BRICK-KILN.

1,159,062.

Specification of Letters Patent.

Patented Nov. 2, 1915.

Application filed November 25, 1914. Serial No. 873,877.

To all whom it may concern:

Be it known that I, FRANK WILLIAM MILES, a citizen of the United States of America, residing at St. Louis, in the State of Missouri, have invented certain new and useful Improvements in Brick-Kilns, of which the following is a specification.

This invention relates to kilns for burning brick tiles and other earthenware products and has for its primary object the provision of a kiln of the character set forth which shall be adapted for use with producer gas or fuel of similar nature.

The primary object of this invention is to provide a kiln of the character set forth which shall be adapted to burn the articles placed therein evenly and thoroughly and without waste.

A further object of this invention is to provide a kiln adapted at all times to have therethrough a perfect draft insuring the even heating of the kiln.

A still further object of this invention is to provide means for causing the combustion of the fuel in such a manner as to prevent all smoke issuing from the kiln.

With these and other objects in view as will hereinafter appear, this invention consists in the peculiar construction and combination of the various related parts of the brick kiln as hereinafter set forth and more particularly designated in the appended claims.

Referring to the accompanying drawings forming a portion of this specification and wherein similar reference numerals indicate similar parts wherever used; Figure 1 is a vertical section through a kiln embodying my invention; Fig. 2 is a longitudinal vertical section therethrough, and Fig. 3 is a horizontal section showing the floor plan thereof.

The numeral 4 designates the outer wall of the kiln which may be of any approved type and provided with an arch-roof 5 having therein a plurality of openings 6 adapted to be closed by means of members 7 inserted therein.

The floor 8 of the kiln is provided with a plurality of openings 9. These openings are so located and arranged that they communicate with an under floor passage-way 10 which in turn communicates by means of ports 11 and 12 with a large central stack flue 13. The total area of the openings 9

in the floor of the kiln equals the area of the stack 14, thus providing equal inlet and outlet openings for the draft which insures a perfect draft at all times through the kiln.

Adjacent the stack flue 13 and located on either side thereof and separated therefrom by means of walls 15 and 16 are air flues 17 and 18 having extending therefrom at suitable intervals transverse passages 19 which extend upwardly adjacent the side wall of the kiln as at 20 and into the kiln proper. At that point where the air duct 20 enters the body of the kiln, there is provided a vertical wall 21 extending upwardly for a short distance within the kiln and forming a pocket 22 open at its upper end 23.

Upon either side of the air flues 17 and 18 are gas flues 24 and 25 adapted to be fed in any suitable manner with producer gas or other suitable fuel. In communication with the flues 24 and 25 are a plurality of upwardly extending passageways 26 which by means of a short vertical extension 27 thereof communicates with the pocket 22 formed between the wall 21 and the arch 5 80 of the kiln.

The operation of the kiln is as follows: The bricks are placed within the kiln body in any suitable manner, care being taken, however, to arrange the piles of bricks so as not to cover any of the floor openings 9. Gaseous fuel is admitted to the flues 24 and 25 from whence it passes through the passageways 26 and 27 up into the pocket 22 where it mixes with the air which has entered through the air flues 17 and 18 and their corresponding passageways 19 and 20. At the pocket 22 formed between the wall 21 and the arch roof 5, the mixture of air and gas is ignited which causes an upwardly arching flame upon either side of the center of the kiln, giving an even distribution of heat and a therefore uniform burning of the bricks or other material placed within.

The location of the air flues 17 and 18 upon either side of the central flue 13 is very important. By means of such location the heat from the smoke flue 13 heats the air passing through the air flues 17 and 18 to a very high temperature, so that when the air which passes through the connecting ducts mixes with the gas within the pocket 22 the heated air causes a rise in temperature of the gas mixing therewith, which superheating of the said gas makes the ignition there-

of easier and the flame correspondingly hotter. By means of this the heat within the kiln is greatly increased, which is a desirable advantage.

5 By means of the construction described the necessity for feeding gas and air to the kiln under pressure is obviated, thus reducing the cost of installation and increasing the efficiency of the kiln.

10 I realize that considerable variation of the specific details of my invention may be resorted to without departing from the spirit thereof, and it is not my intention to limit myself to the construction herein shown and 15 described but to construe the following claims as broadly as the state of the prior art will permit.

What I claim as new is:

1. In a kiln, in combination, a chamber 20 having a bottom the upper part of which is perforated throughout, and provided with connecting flues therebeneath, double side walls forming combustion pockets, means for conducting gas to said pockets, means 25 in the bottom for conducting air to said pockets whereby combustion takes place between both double side walls at each side of the chamber, and a main flue beneath the perforated bottom communicating with the flues 30 leading from the perforations whereby the products of combustion pass evenly over the material to be treated from both sides of the chamber and thence out through the per-

forations in the bottom to said main flue, 35 said air conducting means leading to the combustion pockets being relatively close to and substantially parallel with the flues leading from the perforations in the bottom to the main flue.

2. In a kiln, in combination, a chamber 40 having a bottom the upper part of which is perforated throughout, and provided with connecting flues therebeneath, double side walls forming combustion pockets, means 45 for conducting gas to said pockets, means in the bottom for conducting air to said pockets whereby combustion takes place between both double side walls at each side of the chamber, and a main flue beneath the perforated bottom communicating with the flues 50 leading from the perforations whereby the products of combustion pass evenly over the material to be treated from both sides of the chamber and thence out through the perforations in the bottom to said main flue, 55 said main flue and air conducting means being positioned closely adjacent each other whereby the air is preliminarily heated before going to the combustion pockets.

In testimony whereof I affix my signature 60 in presence of two witnesses.

FRANK WILLIAM MILES.
